ABSTRACT

Ornaments such as greeting cards are illuminated by incandescent lamps powered by disposable batteries. The battery is provided with a recess in its casing and has its output terminals disposed therein. The base of the incandescent lamp is adapted to be received by the recess in the battery and lamp contact terminals disposed on the base engage the battery output terminals in the recess and thus detachably electrically connect the lamp to the battery and energize the lamp to produce light.

6 Claims, 9 Drawing Figures

Inventor..

CHARLES FRANC.

APPARATUS FOR ILLUMINATING ORNAMENTS

SUMMARY OF THE INVENTION

Ornaments such as greeting cards are provided with detachable self powered means for illuminating the ornaments. The means includes an incandescent lamp adapted for detachable engagement with a disposable battery.

BRIEF DESCRIPTION OF THE DRAWINGS

In the drawings:

FIG. 1 is a front view of one form of my invention;

FIG. 2 is a side view of the form shown in FIG. 1;

FIG. 3 is an exploded front perspective view of a second form of my invention;

FIG. 4 is an exploded front perspective view similar to FIG. 3 but showing a modification thereof;

FIG. 5 is a front view of a housing used in a third form of my invention;

FIG. 6 is a front view of a third form of my invention;

FIG. 7 is a side view of the form shown in FIG. 6; and

FIGS. 8 and 9 are exploded front perspective views of further modifications of FIG. 3.

DETAILED DESCRIPTION OF PREFERRED EMBODIMENTS

Referring now to FIGS. 1-2, there is shown a flat circular ring or annulus 10 which includes a battery having positive and negative terminals disposed in a recess 12. An incandescent lamp 14 having the general shape of a flame has a base 16 adapted to be detachably placed in the recess to engage the terminals and thus be energized and produce light. The battery can form the entire annulus, or the battery can form a portion of the annulus with the remainder as a shell.

FIG. 3 shows a half round incandescent lamp 14 having the general shape of a flame with prongs 20 in base 22 spaced apart and bent up to make contact with corresponding spaced negative and positive terminals in a base receiving recess 24 in one end of a rectangular battery 26. Alternatively, the lamp prongs can extend outward to fit into corresponding recesses 30 in battery 26 whereby each prong is placed in contact with a corresponding terminal of the battery as shown in FIG. 4. Further as shown in FIG. 8, lamp 14 can have a hollow sleeve 60 into which battery 62 can slide as shown. The bulb can be round with cylindrical sleeve and battery as desired. If desired as shown in FIG. 9, the battery can hold the sleeve and the bulb can slide in as shown.

FIG. 5 shows a hollow plastic housing 40 with an open circular protective piece 42 for a lamp bulb and a snap lock 44 to hold the bulb in position as well as a holder 46 for a battery.

FIG. 6 shows the structure of FIG. 5 with a lamp 48 engaged at its base by the snap lock and a battery 50 in the holder.

FIG. 7 is a side view of the structure of FIG. 6 with one prong or wire 52 of the lamp engaging the negative terminal of the battery and another flexible prong 54 which is normally spaced away from the positive terminal, but can be manually pressed into contact to energize the lamp.

It is to be understood that this concept can be applied to various types of ornaments aside from greeting cards, such as gift wrappings, packaging and product ornamentation.

While only a few embodiments of the present invention have been shown and described, it is to be understood that many changes and modifications may be made thereunto without departing from the scope and spirit of the invention.

What I claim as new is:

1. An apparatus for illuminating an ornament, such as a greeting card, gift packaging and the like, comprising:

a flat, rectangular battery having a rectangular sleeve extension integrally formed with the battery casing thereof, said sleeve extension being the negative output terminal of said battery, a circular positive output terminal of said battery being disposed at the bottom of said sleeve extension on the surface of said battery casing; and

an incandescent lamp having the general shape of a flame and a substantially rectangular base shaped so as to be slidable into said sleeve extension, said base having a first contact terminal comprising the sides of said base and a second contact terminal comprising a circular contact terminal disposed on the bottom of said base, so that said first and second contact terminals engage said negative and positive battery terminals respectively when said lamp is inserted into said sleeve extension, thereby detachably connecting said lamp to said battery and energizing said lamp to produce light.

2. An apparatus for illuminating an ornament, such as a greeting card, gift packaging and the like, comprising:

a flat, substantially rectangular battery having a semi-cylindrical recess provided in the battery casing thereof, the curved wall of said recess comprising the negative output terminal of said battery, and the planar wall of said recess comprising the positive output terminal of said battery; and

an incandescent lamp having the general shape of a flame and a substantially semi-cylindrical base having first and second output terminals affixed thereto disposed adjacent the planar and curved sides of said base respectively, said base being slidable into said recess provided in said battery so that said first and second contact terminals engage said positive and negative battery terminals respectively when said lamp is inserted into said recess, thereby detachably connecting said lamp to said battery and energizing said lamp to produce light.

3. The apparatus as recited in claim 2 wherein said first and second output terminals affixed to said lamp base are rectangular in shape.

4. An apparatus for illuminating an ornament, such as a greeting card, gift packaging and the like, comprising:

a flat, substantially rectangular battery having a pair of rectangular-shaped slots disposed in the housing thereof, the internal walls of each of said slots comprising the positive and negative output terminals respectively of said battery; and

an incandescent lamp having the general shape of a flame and a base having first and second downwardly depending output terminals affixed thereto, said output terminals being rectangularly shaped so as to be slidably received by said slots in said battery casing, so that said first and second contact terminals engage said positive and negative battery terminals respectively when said lamp is inserted into said pair of slots, thereby detachably connecting said lamp to said battery and energizing said lamp to produce light.

5. An apparatus for illuminating an ornament, such as a greeting card, gift packaging and the like, comprising:

a flat, substantially rectangular battery having a circular positive output terminal disposed on the top surface thereof, and a negative output terminal comprising the battery casing thereof; and

an incandescent lamp having the general shape of a flame and a substantially rectangular-shaped base having a rectangular sleeve extension integrally formed with said base for slidably receiving said battery, said lamp having a first contact terminal comprising said rectangular sleeve extension and a second contact terminal comprising a circular contact terminal disposed on the bottom surface of said base, so that said first and second contact terminals engage said negative and positive battery terminals respectively when said lamp is inserted over said battery, thereby detachably connecting said lamp to said battery and energizing said lamp to produce light.

6. An apparatus for illuminating an ornament, such as a greeting card, gift packaging and the like, comprising:

a flat, substantially annular battery having a substantially rectangular, radially disposed, recess provided in the casing thereof, one planar wall of said annular battery comprising the positive output terminal thereof and the other

planar wall of said battery comprising the negative output terminal thereof; and
an incandescent lamp having the general shape of a flame and having a substantially rectangular base with first and second vertically upwardly disposed contact terminals affixed thereto, said base being slidably received by said

recess in said battery so that said first and second contact terminals engage said positive and negative battery contact terminals respectively when said lamp is inserted into said recess, thereby detachably connecting said lamp to said battery and energizing said lamp to produce light.
